OHIO.

FIREARM ATTACHMENT.

1,371,899.

Specification of Letters Patent. Patented Mar. 15, 1921.

Application filed August 20, 1917. Serial No. 187,223.

To all whom it may concern:

Be it known that we, BENJAMIN L. JENKS, JAMES L. CAMERON, and LAWRENCE E. YAGGI, citizens of the United States, residing at Cleveland, in the county of Cuyahoga and State of Ohio, have invented a certain new and useful Improvement in Firearm Attachments, of which the following is a full, clear, and exact description.

10 The present invention relates particularly to an attachment in the form of a frame or shoulder rest or brace designed to be attached to a gun, such as a military rifle, and provided with auxiliary bolt throwing and trigger operating devices which are located below the gun proper so that they can be operated by the operator located below the gun and wholly concealed and protected by a trench or the like. Our invention is 15 adapted to be used in connection with various kinds of fire arms, and has particular utility in connection with a so-called sitascope, constituting the subject matter of applications, Serial No. 66,200, filed December 25 10, 1915, and Serial No. 37,625, filed July 1st, 1915, in the names of Lawrence E. Yaggi and James L. Cameron, two of the joint applicants herein.

One of the objects of the present invention is to provide an attachment which can be applied to a gun, such as a military rifle, and including a shoulder rest with portions to be engaged by the shoulder and hand of the operator so that the gun is held or supported firmly upon the shoulder, in such a manner as to leave the hands free of strain or load, and which is so constructed that when the gun is fired, the recoil will not cause any material shock to the operator. 40 Additionally the invention aims to provide on the attachment, devices for operating the trigger and bolt of the gun, these devices being so mounted that they have the same or similar movements as the gun trigger and gun bolt respectively, so that the gun can be fired by the operator from a relatively lowered position, with the same hand movements that are required when the gun is operated in the ordinary manner.

The above and numerous additional objects are accomplished by our invention which may be briefly summarized as consisting in certain novel details of construc-

tion and combinations and arrangements of parts which will be described in the specification and set forth in the appended claims.

These results are obtained in connection with the use of the said sitascope, by attaching to the butt and stock of the firearm a combination sub-stock and shoulderbrace, having a lowered, auxiliary bolt-throwing device and an extension trigger, illustrated in the accompanying drawing, in which—

Figure 1 is a side elevation of a military rifle to which is attached our sub-stock and shoulderbrace, showing the lowered bolt-throwing device and the extension trigger.

Fig. 2 is a rear end elevation of the butt of the gun with our sub-stock and shoulderbrace attached thereto and the attachment for throwing the bolt and ejecting the shells and replacing empty shells with loaded shells from the magazine of the gun.

Fig. 3 is a cross-section of the stock of the gun, showing in elevation the holding device clamp, around the stock of the gun and the attachment for throwing the bolt and ejecting the shells and introducing loaded shells from the magazine of the gun.

Fig. 4 is a side elevation of the bolt throwing device.

Fig. 5 is an end elevation of the bolt throwing device, shown as in Fig. 2.

Fig. 6 is an end elevation of the lowered bolt throwing device, as seen from the muzzle end of the gun.

Fig. 7 is a side elevation of a clevis joint used in attaching the sub-bolt to the main bolt of the gun, by means of two connecting rods.

Fig. 8 is an end elevation of the clevis joint shown in Fig. 7.

Fig. 9 is a detailed side elevation of the claw engaging the ball on the bolt lever of the gun, and being attached to the upper end of the two connecting rods as shown in Fig. 1.

Fig. 10 shows a detailed side elevation of the terminal of the trigger pulling device in connection with the trigger of the gun.

Fig. 11 is a detailed plan of the terminal of the trigger pulling device showing the spool in connection with the trigger.

Similar letters refer to similar parts throughout the several views.

In Figs. 1, 2 and 3,
(a) is a rifle or other small arm.

(b) is the frame of the sub-stock and shoulder-brace, having a shoe (c) rigidly attached to the frame (b) and being quickly attachable to and detachable from the gun 5 (a) by the adjustable clamp (d).

The shoe (c) is reinforced and strengthened by the metal pieces, (e) which always maintain a uniform, rigid connection between the gun (a) and the frame (b).

10 (f) is a clamp around the stock of the gun (a) rigidly attaching and holding the frame (b) to the gun (a) but being quickly attached thereto and detached therefrom, by means of the swivel screw and nut (g) 15 Fig. 3.

(h) is a strengthening cross brace between the two legs of the brace (b) and it carries the sub-bolt (i) which revolves and slides on the rod (j), which is rigidly attached to 20 the crosspiece (h) by the stands (k).

The auxiliary sub-bolt (i) operates substantially parallel to the bolt of the gun (a) and has two arms (l) and (l'), which are attached by means of clevis joints (m) and 25 (m') to the two connecting rods (n) and (n') the upper ends of which rods terminate in adjustable concave claws (o) and (o') which are quickly attachable to and detachable from the ball on the arm (a') 30 of the gun bolt. The two hemispherical claws (o) and (o') are made to engage the ball by means of the bolt and the wing nut (p). The arm (l) of the sub-bolt terminates in a ball (l'') forming a handle.

35 (q) is the extension trigger which operates the trigger on the gun (a) by means of rocking levers and connecting rods as shown in Fig. 1, and engaging the trigger (a'') of the gun (a) by means of the revolving spool (r). The sub-trigger (q) is 40 protected by the guard (s). The frame (b) is formed as shown at (t), so as to support and hold the gun (a) comfortably on the shoulder of the operator in a concealed and 45 protected position. The frame (b) may be padded, where it comes in contact with the shoulder of the operator as at (u).

(v) is a handle grip on the frame (b) below the trigger guard (s).

50 (b') is an extension of the brace and sub-stock for the purpose of keeping the sitascope and sub-magazine from being damaged by hitting the bank of the trench, and also to form a handle for more easily holding and guiding the gun.

(S) is an independent reflecting or refracting sighting device, called a sitascope. The sub-bolt (i) operates substantially parallel to the bolt of the gun (a) and in a 60 similar manner.

It will be observed that the sub-bolt (i) has the same movements as the bolt of the gun, and that the operator will revolve and move the sub-bolt axially by manipulating the

lever or handle (l), giving this handle precisely the same movements as the operator would give to the bolt operating lever (a') if the gun were used in the ordinary manner without the attachment. Likewise the same movement is given to the extension trigger 65 as the operator would give to the trigger of the gun if used without the attachment. These features are of considerable importance, as it enables the operator to manipulate a gun with this attachment applied, as 70 easily as he would operate the gun without the attachment, and practically no time is required to enable the operator to secure excellent results when operating the gun 75 through the attachment from a position below the gun.

The provision of the shoulder brace as shown, and the forward hand grasping portion or hand grip (v) enables the operator to hold the gun steady and firmly while operating or firing, with the hand engaging the grip (v) practically free of strain or load, since the shoulder rest is so constructed as to engage the part and to extend over the shoulder so that the latter will sustain the 85 load, and the whole device is so constructed that the recoil following firing does not cause any shock to the operator, the recoil being absorbed by a backward rotation of the gun rather than by a direct thrust on 90 the body of the operator.

A further advantage, and one which will be apparent from the drawings, is the fact that the device can be attached to the gun 95 easily and effectively, and without requiring any special gun construction, or of altering its construction.

We claim—

1. An attachment for a gun having means for attachment to the butt of the gun stock, 105 and comprising a lower rear shoulder engaging portion and a forward hand grip, the shoulder engaging portion being beneath and forward of said attaching means so that when attached to a gun and applied to the 110 shoulder of the operator the gun stock will be above his shoulder.

2. An attachment for a gun comprising a shoulder rest having parts adapted to be attached to the gun at two points, one forward 115 of the other, and having a shoulder engaging part with a portion of said last mentioned part shaped to engage the front of the shoulder of the operator, and another portion shaped to simultaneously engage the 120 top of the shoulder, the shoulder engaging part being beneath and forward of the rear point of attachment to the gun.

3. An attachment for a gun comprising a frame having means for attachment to the 125 butt of the gun stock, and at a point forward of the butt, and said frame having a lower portion adapted to rest upon and engage

the shoulder of the operator, said lower portion being beneath and forward of the means for attachment to the butt of the gun stock.

4. A gun attachment comprising a frame having means for attachment to a gun stock at the butt thereof and forwardly of the butt, and said frame having beneath and between the two points to be attached to the gun, a lower portion adapted to rest upon and engage the shoulder of the operator, and another portion forward of the shoulder engaging portion and adapted to be grasped by the hand of the operator.

5. A gun attachment comprising a frame having at the rear, means for forming a detachable connection with the butt of a gun stock, and having means for forming clamping engagement with the stock forward of the butt, and said frame having beneath and forward of the means for forming connection with the butt of the stock a lower rear shoulder engaging portion and a forward hand grip whereby the attachment may be firmly held against the shoulder of the operator.

6. An attachment for a gun comprising a

frame having forward and rear portions adapted to be attached to the gun, and one constituting a shoulder engaging member, a transverse member extending between said portions, a sub-bolt mounted on said transverse member for rotary movement and end-wise sliding movement, means for shifting said sub-bolt, means for connecting the same to the bolt of the gun, and a trigger operating member supported on the forward portion.

7. An attachment for a gun comprising a frame having forward and rear portions adapted to be attached to the gun, and having a shoulder engaging portion beneath and between the two portions to be attached to the gun, and a sub-bolt carried by the frame and mounted thereon for rotary and end-wise movement.
